(57) **CLAIM**

The ornamental design for a cartridge body for modular cartridge assembly, substantially as shown and described.

DESCRIPTION

FIG. 1 is a perspective view of a cartridge body for modular cartridge assembly showing the claimed design.

FIG. 2 is a front view of the cartridge body for modular cartridge assembly.

FIG. 3 is a rear view of the cartridge body for modular cartridge assembly.

FIG. 4 is a left side view of the cartridge body for modular cartridge assembly.

FIG. 5 is a right side view of the cartridge body for modular cartridge assembly.

FIG. 6 is a top view of the cartridge body for modular cartridge assembly; and,

FIG. 7 is a bottom view of the cartridge body for modular cartridge assembly.

The portions of the cartridge body for modular cartridge assembly shown in broken lines depict environment and are for illustrative purposes only. The broken lines form no part of the claimed design.
